UNITED STATES PATENT OFFICE.

NEAL W. WHITBECK, OF DETROIT, MICHIGAN, ASSIGNOR TO MICHIGAN LUBRICATOR COMPANY, OF DETROIT, MICHIGAN, A CORPORATION OF MICHIGAN.

VALVE.

1,174,211.

Specification of Letters Patent.

Patented Mar. 7, 1916.

Application filed April 12, 1915. Serial No. 20,899.

To all whom it may concern:

Be it known that I, NEAL W. WHITBECK, a citizen of the United States of America, residing at Detroit, in the county of Wayne 5 and State of Michigan, have invented certain new and useful Improvements in Valves, of which the following is a specification, reference being had therein to the accompanying drawings.

10 The invention relates to valves and resides in the novel connection between the valve casing and the valve stem, and in certain details of constructions, arrangements and combinations of parts as will more fully 15 hereinafter appear.

In the drawings,—Figure 1 is a longitudinal, central section through a valve embodying the invention; Fig. 2 is a sectional plan view thereof; and Figs. 3, 4 and 5 20 illustrate certain details of construction.

A designates the casing of the valve and B the plug valve therein, these parts for the purpose of the invention being of any suitable construction. In the structure 25 shown, however, the valve is of the shell type.

C is the inlet for the casing and D the outlet.

E is the valve opening, which upon rotation of the valve is adapted to be moved into or out of registration with the outlet D. Rigidly attached to the valve is a stem F that extends out through the neck G of the 30 valve casing. Within the neck G is a bearing H having a central aperture I of a size to nicely fit the stem.

J is an opening in the bearing communicating with the aperture I, and K is a lug on the valve stem adapted when the latter 40 is inserted through the aperture I to pass through the opening J, so as to be positioned above the outer face L of the bearing H.

M is a key which closes the opening J.

With the parts so far described, when it 45 is desired to engage the valve with the casing, the stem is inserted through the aperture I and after the lug K passes above the outer face L of the bearing H, the stem is rotated to move the lug K out of registration with the opening J and the key M then 50 inserted into the opening J. The valve is supported from the bearing H by the lug K. Below the lug K is a shoulder N spaced from the lug a sufficient distance to allow the

bearing H to be positioned therebetween. 55 When the key is inserted in the opening J the lower edge of the key rests upon the shoulder N. It is of course, desirable to have stops for positioning the opening and closing movements of the valve, and to this 60 end the key M is made of a sufficient length to project above the bearing H into the path of the lug K, so that when the valve is turned in one direction its movement will be limited by the lug K contacting with one 65 side of the key M, while when turned in the opposite direction the movement will be limited by the lug K contacting with the opposite side of the key. The parts are so proportioned that in the different positions of 70 contact of the lug with the key, the valve will be in its open and closed positions respectively.

The neck G is provided with the usual gland nut O having the packing material P. Below the packing P is arranged a washer Q which seats on a ledge R in the upper edge of the neck G. By this arrangement the packing P may be tightly compressed without in any way affecting the 80 connection between the valve stem and the neck G.

The form of valve described is a very simple and efficient structure, and while the preferred form of the valve has been illustrated, I do not desire to limit the protection to the exact structure shown. 85

What I claim as my invention is:—

1. In a valve, the combination with the casing having a neck portion, a centrally apertured bearing in the neck portion having an opening therethrough communicating with the aperture, a plug valve within the casing, a stem for actuating said valve arranged within the aperture of the bearing and having a lug projecting laterally therefrom and engaging the outer face of said bearing, said lug being of a size to be inserted through the opening, and a key insertible through the neck portion for closing said opening. 90

2. In a valve, the combination with the casing having a neck portion, a centrally apertured bearing in the neck portion having an opening therethrough communicating with the aperture, a plug valve within the casing, a stem for actuating said valve arranged within the aperture of the bearing 105

and having a lug projecting laterally therefrom and engaging the outer face of said bearing, said lug being of a size to be inserted through the opening, and a key for closing said opening, projecting above the outer face of the bearing into the path of the lug, said key being positioned to form stops for limiting the opening and closing of the valve.

10 3. In a valve, the combination with the casing having a neck portion, of a centrally apertured bearing in the neck portion, said bearing having a flat outer face and provided with an opening therethrough communicating with the aperture, a plug valve within the casing, a stem for actuating said valve arranged within the aperture of the bearing and having a lug projecting laterally therefrom and engaging the outer face of the bearing, said lug being of a size to be inserted through the opening, and a key for closing said opening projecting above the outer face of the bearing and positioned to form stops coöperating with the lug to limit the opening and closing of the valve.

15 4. In a valve, a casing having a neck portion, a centrally apertured bearing formed within and integral with the neck portion, said bearing having a flat outer face and provided with an opening therethrough, a plug valve within the casing, a stem for actuating said valve arranged within the aperture of the bearing, a shoulder on the stem below the bearing, a lug on the stem 20 engaging the outer face of the bearing and acting to support the valve, said lug being of a size to be inserted through said opening, and a key insertible within the opening and supported upon said shoulder, said key 25 projecting above the outer face of the bearing into the path of the lug and forming stops for limiting the opening and closing of the valve.

30 5. In a valve, the combination with the casing having a neck portion, a centrally apertured bearing in the neck portion having an opening therethrough communicating with the aperture, a plug valve within the casing, a stem for actuating said valve arranged within the aperture of the bearing and having a lug projecting laterally therefrom and engaging the outer face of said bearing, said lug being of a size to be inserted through the opening, a key for closing said opening, a gland nut engaging the neck of the casing and packing within said gland nut, said neck having a shoulder, and

a collar engaging said seat and against which the packing is forced.

5 6. In a valve, the combination with a casing having an apertured bearing provided with an opening therethrough communicating with the aperture, a plug valve within the casing, a stem for actuating said valve, arranged within the aperture of the bearing and having a lug projecting laterally therefrom and engaging the outer face of said bearing, said lug being of a size to be inserted through the opening, and a closure for the opening.

10 7. In a valve, the combination with a casing having an apertured bearing provided with an opening therethrough communicating with the aperture, a plug valve within the casing, a stem for actuating said valve, arranged within the aperture of the bearing and having a lug projecting laterally therefrom and engaging the outer face of said bearing, said lug being of a size to be inserted through the opening, and a closure for the opening, and means for limiting the motion of the valve.

15 8. In a valve, the combination with a casing having a neck portion, a centrally apertured bearing in the neck portion having an opening therethrough communicating with the aperture, a plug valve within the casing, a stem for actuating said valve arranged within the aperture of the bearing and having a lug projecting laterally therefrom engaging the outer face of the bearing, said lug being of a size to be inserted through said opening, a key for closing said opening, and a shoulder on the stem below the bearing.

20 9. In a valve, the combination with a casing having an apertured bearing provided with an opening therethrough communicating with the aperture, a plug valve within the casing, a stem for actuating said valve arranged within the aperture of the bearing and having a lug projecting therefrom and engaging the outer face of the bearing, said lug being of a size to be inserted through the opening, and means retaining said closure 25 against displacement longitudinally of the stem.

25 In testimony whereof I affix my signature in presence of two witnesses.

NEAL W. WHITBECK.
